UNITED STATES PATENT OFFICE

2,381,066

FOLDING PERAMBULATOR

Lawrence Eugene Little, Epsom, England

Application March 24, 1944, Serial No. 527,889
In Great Britain August 14, 1942

3 Claims. (Cl. 280—42)

This invention has been designed to provide a convenient form of portable perambulator. The wheels and their springing can also be made almost instantaneously detachable from the body part, so that the latter can also be used without difficulty as the body part of a cot.

In the preferred form the perambulator body is constructed of rigid panels of light alloy or other light sheet or molded material hinged together, so that it will fold laterally. The wheels are independently mounted so that they can be pivoted into positions alongside the body and the handle can also collapse laterally and fold over the body. The folding hood can also be laterally collapsible or may be removable. The perambulator can in this way be of pleasing and substantially normal appearance when set up for use, while in a typical case it will fold into a width of a foot or less with all the parts within or substantially within the contour of the sides. The above and other parts of the invention are embodied in a typical form to be described with reference to the accompanying drawings. The parts for which a patent is desired are those delimited by the claims.

In the drawings:

Fig. 1 is a perspective view of the perambulator set up for use,

Figs. 2, 3 and 4 are respectively a side elevation, an end view and a plan of the same in folded condition,

Fig. 5 is a view of the body cut away to show the floor and seat construction,

Fig. 6 shows the same partially folded and

Figs. 7 and 8 are enlarged partly sectional side and rear elevations of the wheel springing.

Figs. 1 and 5 show the almost normal appearance when set up for use. The body has rigid sides 1 joined by foldable end sections. Each end section consists of narrow inward flanges 2 on the sides 1 to which are hinged the end panels 3, 4, 3, hinged to one another so that the ends are rigid when straightened out as in Figures 1 and 5, and folded as in Figure 6. The centre panels 4 are in telescopic (used broadly) relationship to another, that is slide together or apart, being mounted together with the central angular or L shape part 5 constituting a seat section to slide on a tubular longitudinal member 6. The side sections of the seat are formed of plates 7, 8 hinged together and to the bottom of the well, so as to fold as indicated in Fig. 6. The bottom of the well is formed of plates 9 hinged to the side panels and meeting at the longitudinal centre line. Means, repre-

sented by blocks 10 can engage the tube 6 locking the assembly. To cover the well when desired removable slats 11 may be used. Thus to fold the body, the slats 11 (if used) are removed, the plates 7, 8 and 9 folded up and the panels 4 pushed towards one another, until the parts are all neatly enclosed between the side panels 1 as these approach one another.

Loose upholstery 12 may be secured by press studs 13 if desired and the tube 6 may serve as an umbrella holder.

The body may, however, be formed to collapse laterally in many other ways in accordance with the main ideas underlying the invention.

The handle 14 is pivoted to the sides 1 and may collapse, for example, by one side telescoping into the grip 15. The hood may be removed, or may fold about hinges at 16 in the hoop as indicated at Figs. 3 and 4.

18 The wheels 17 are independently mounted and sprung. For each wheel, one part of a detachable ball and socket connection 18 is secured about midway up the perambulator body and a bracket 19, forming one part of an instantly detachable fastening, at or near the bottom. The wheel hub is mounted on a stub axle 20 carried by a bracket 21 at the bottom of a telescopic axle post 22 housing a short and rather powerful spring 23 adjusted to the weight and a larger spring 24 to take road shocks. At the top of the axle post is the second part of the ball and socket connection 18. Secured to the lower end of the upper member of the axle post 22 is a bracket 25 which forms the second part of the instantly detachable fastening, being held to the bracket 19 by a spring loaded anchor pin 26. Brackets 21 and 25 are both extended to give leverage for keeping the wheel in permanent alignment, the bracket 21 carrying a guide post 27 having an adjustable stop

20 28. The post 27 is slideable in the bracket 25 or a part carried thereby while the stop 28 cooperating with the bracket 25 limits the upward movement of the body. The axle posts 22 are arranged to provide front and back pairs for the wheels 17 in which the back wheels have a wider track than the front wheels. It will be clear that by withdrawing the anchor pins 26 the assembly can be freed at the bottom and either withdrawn completely at the joint 18 or swung round so that the wheels overlap alongside the sides of the body as shown at Figs. 2 to 4.

I claim:

1. A perambulator including a collapsible body comprising rigid sides, foldable end sections hingedly connected with the sides, a longitudinal

support, seat sections slidable on said support and hingedly connected with said end sections respectively, bottom sections hingedly connected with said sides respectively along their outer edges and their inner edges capable of resting on said support, and additional foldable seat sections arranged between the end and bottom sections and hingedly connected with the bottom sec-

tions respectively to combine with said first seat sections to complete the seats.

2. A perambulator as set forth in claim 1, wherein each of said first seat sections is L shape.

3. A perambulator as set forth in claim 1, and a telescopic handle whose opposite ends are connected with said sides respectively.

LAWRENCE EUGENE LITTLE.
